(57) **CLAIM**

The ornamental design for an upright vacuum cleaner dirt separator front, as shown and described.

DESCRIPTION

FIG. 1 is a perspective view of a design for an upright vacuum cleaner dirt separator front showing our new design;
FIG. 2 is a front view thereof;
FIG. 3 is a rear view thereof;
FIG. 4 is a left side view thereof;
FIG. 5 is a right side view thereof;
FIG. 6 is a top view thereof; and,
FIG. 7 is a bottom view thereof.

The portion of the drawings in phantom lines are shown for purposes of illustration and form no part of our new design.
